Specification of Letters Patent

Patented Mar. 9, 1915.

Application filed January 21, 1911. Serial No. 808,388.

To all whom it may concern:

Be it known that we, ROBERT E. L. JANNEY, residing at Chicago, in the county of Cook and State of Illinois, and EDMUND P. KINNE, residing at Alliance, in the county of Stark and State of Ohio, both citizens of the United States, have invented certain new and useful Improvements in Couplers, of which the following is a specification.

10 Our invention relates to improvements in car couplers and has particular reference to a car coupler having a pivoted knuckle opener or kicker. This embodiment of the invention is shown in connection with a 15 coupler having a locking block adapted for vertical movement on a rib within the coupler head, the lock-setting and anti-creeping means being applied directly to said block and rib, said block being the means used for 20 keeping the pivoted opener in place.

We are aware that pivoted, transversely operating openers for couplers are not new but such openers heretofore have been mounted without such freedom of movement 25 as will permit the opener to follow the path of travel of the knuckle tail during the opening movement. During the opening or closing movement of the knuckle tail any particular point on the tail follows a line 30 which is an arc of a circle, the axis of which is the axis of the knuckle pin. Therefore it will be seen that in order to avoid frictional resistance in the opening operation the opener should follow a path which is at 35 all times tangent to the circle described by the knuckle tail. If it is tangent to the circle at one point only, say for example at the beginning of the opening movement, then the leverage of the opener becomes less 40 and less as its path becomes less tangent to the path of the knuckle tail. In order to make this clear it has been illustrated dia-grammatically in the drawings.

Therefore one of the important features 45 of my invention is the provision of a transversely pivoted opener which shall be so arranged as to follow the tail of the knuckle and to exert at any point in the opening movement a force tangent to the path of 50 travel of the knuckle tail. This novel result is accomplished by the manner in which the kicker is pivoted, all of which will be later described.

It is a well known deficiency in couplers 55 that after continued use the parts become

worn to such an extent that the knuckle cannot be thrown completely open by the usual knuckle opener, this necessitating the manual throwing of the coupler knuckle with the attendant element of danger to the workman. Therefore we have provided in our coupler means for compensating wear. A further advantage is the provision of means in connection with a block lock coupler, such as shown in the drawings, for positively unseating the lock from the lock-set during the opening movement of the knuckle and preventing its becoming reseated on the lock-set during the closing movement. Another advantage is in the location of the kicker 70 with relation to the locking-block whereby the weight of the kicker is used to assist in seating the lock on the lock-set.

Other and further advantages will appear hereinafter and be particularly pointed out 75 in the claims.

Our invention will be more readily understood by reference to the accompanying drawings, wherein.

Figure 1 is a plan view of a coupler embodying our invention, the interior parts being shown in dotted lines. Fig. 2 is a front view showing the coupler knuckle open. Fig. 3 is a view similar to Fig. 1, but with the top of the coupler head removed to 80 show the arrangement of parts. Fig. 4 is a sectional view on the line 4-4 of Fig. 3. Fig. 5 is a sectional view on the line 5-5 of Fig. 3, showing the locking block on the lock-set. Fig. 6 is a view taken on the same line as Fig. 5, but showing the locking block 85 in normal locking position. Figs. 7, 8 and 9 show the positions of the knuckle opener and its trunnions at respectively the normal inoperative position, the beginning of the 90 opening movement, and the complete movement. Fig. 10 shows by diagram the operation of our knuckle thrower with respect to the knuckle tail. Fig. 11 is a similar dia-grammatic view showing the action of a 95 rigidly mounted transversely operated knuckle thrower. Fig. 12 is a section through the coupler just above the knuckle showing the knuckle in plan, and Fig. 13 is a section taken on the same line showing the 100 relative position of the lock to the groove in the knuckle when the knuckle is partly open.

Referring more particularly to the drawings it will be seen that our coupler is composed of a coupler shank 20, having a head 110

provided with the usual guard arm 21, knuckle retaining portion 22 and with an internal recess 23. The knuckle 24 is pivoted within the head by means of a knuckle pin 24^a. The knuckle 24 is provided with a tail portion having a locking face 25, on the reverse side of which provision is made for the accommodation of the knuckle opener later to be described. On the upper surface of 10 the knuckle tail I provide an arc-shaped groove 27, for a purpose to be also later described. This groove 27 is best shown in Figs. 25 and 12. Within the recess 23 in the coupler head, we provide an integral, 15 vertically extending rib 28, having a lock-setting notch or ledge 29 and an anti-creeping abutment 30. A lock 31 is adapted for vertical movement on said rib 28. This lock is provided with a groove 32, said lock having at its lower end a squared portion 33, serving as a seat portion to seat upon the lock-set shoulder or ledge 29. On the opposite side of the groove at the lower end of the lock we provide a hook 34, which hook, 25 together with the abutment 30, prevent the creeping of the lock during normal operation. This lock is provided on its upper surface with a staple 35, with which is connected a lifting link 36, having a clevis 37 30 attached to the upper end thereof. This link 36 is connected to the staple 35 through an elongated slot 38. As is well understood, it is desirable that when the lifting member of a lock has performed its duty of lifting 35 the lock and in some cases throwing the knuckle, it is desirable that said lifter should descend out of the way to prevent possible breakage, but it is also desirable that it should by its position indicate whether the 40 lock is in normal locking position or whether it is on the lock-set. Therefore the slotted connection with the lock provides for the descending of the lifter to nearly its normal position, but still maintains it sufficiently 45 elevated to indicate that the coupler is not locked. On the lower surface of the lock near its front end we provide a projection 39 having a beveled rear face which is adapted for coöperation with the groove 27 50 on the knuckle tail, this means accomplishing the positive unseating of the lock from the lock-set during the opening movement of the knuckle and preventing the reseating of the lock during the return movement of 55 the knuckle tail. As will be seen, the lock is lifted from a point to the rear of its center of gravity. Therefore when the portion 33 reaches a point opposite the notch or ledge 29, it will swing by gravity into such notch. 60 This seating action is made positive by the location of the lock with reference to the lifter later to be described.

As will be seen by reference to Fig. 5, if the lock is lifted to a point where its lower edge is coincident with the notch 29, its up-

per portion will contact the fulcrum arm of the opener and add the weight of the opener to force the lock onto the lock-set. On the opening movement of the knuckle, the projection 39 of the lock, coöperating with the groove 27, will draw the lock off the lock-set ledge 29, the lock dropping a short distance or to such an extent that the squared portion 33 is not opposite the notch 29. This, together with the fact that the lock is held in this position by the coöperation of the projection 39 with the groove 27, obviates the possibility of the lock being again seated on the lock set during the opening movement of the knuckle. This action is illustrated in 70 Figs. 12 and 13. As shown in these views the shape of the groove is such that on the beginning of the opening movement of the knuckle the projection 39 will be contacted with the rear wall 27^a of the groove near the 80 mouth thereof. Due to the eccentricity of the groove with relation to the pivot pin, the lock is drawn forward from its lock-set position and being unsupported at its rear 90 will drop upon the knuckle tail with its bottom below the lock set ledge and remain in this position throughout the opening and closing movements of the knuckle.

When the lock is lifted above its lock set position to swing the knuckle open to its 95 fullest extent, as shown by dotted lines in Fig. 13, it is desired to prevent the lock from again going back on the lock set, and this is accomplished by means of the projection 39 dropping in front of the extension 27^b when 100 the lock drops, while the knuckle is stationary.

The opening movement of the swinging knuckle is limited by means of a stop shoulder 50 upon the bottom of the knuckle tail, 105 which stop engages the front wall of the recess 23, as shown in Fig. 4 of the drawings.

We will now proceed to describe our novel knuckle opener or kicker. Integral bearings 40, 41, are provided within the recess 23 of 110 the coupler head, these bearing recesses being of novel shape and position with relation to the axes of the coupler.

As will be seen by reference to Fig. 5, the bearing recesses have their sides open to the 115 interior of the coupler head and that they are considerably longer than wide. Also that they are not in a horizontal plane, neither are they in a plane coincident with the longitudinal axis of the coupler. This 120 is best shown in Fig. 3. Within these bearings is mounted an opener having trunnions 42, 43, with a downwardly and sidewardly projecting foot or kicker 44, and an arm 45 arranged at substantially right angles to the 125 kicker portion 44. The arm 44 is adapted for contact with the upper portion of the locking block previously described and is best shown in Fig. 5. It will be noted that the peculiar mounting of the knuckle 130

thrower is designed for the accomplishment of a specific result; that is, the elimination of friction between the opener and knuckle tail, the parts being so arranged that the 5 full power of the opening lever is exerted most advantageously.

In many couplers of this type heretofore the opener has been mounted in rigid bearings transversely of the coupler; that is, in 10 bearings parallel with the longitudinal axis of the coupler. Therefore the force exerted to swing the knuckle is partly lost through friction and the imperfect leverage exerted on the tail of the knuckle. This is illustrated 15 diagrammatically in Fig. 11. In this view let the points A, B, represent the travel of the knuckle tail and let the arrow C, D, indicate the direction of force applied by the knuckle opener. It will be seen that at the 20 point E, the extreme leverage for the swinging of the knuckle is exerted, that at the point F, this leverage has become less and that at the point G, the leverage exerted to open the knuckle is very slight; that whereas, at the beginning of the movement the leverage was equal to the distance from A to H, whereas at the point G, of the movement 25 the leverage was only from H to J.

The operation of our opener is illustrated 30 diagrammatically in Fig. 10. Allowing the travel of the knuckle tail to be represented as between the points A', B', and the direction of force applied by the opener by C', D', it will be seen that at the point A', the 35 full leverage between the points A', H', is secured, due to the tangential movement of the opener with respect to the arc of the circle described by the knuckle tail in its opening movement. At the point F', the 40 direction of force of the opener is still tangent to the arc of the circle and at the point G' it is still tangent and thus the full leverage of the opener is secured at any point. This action is secured by the peculiar mounting 45 of the opener in its loose bearings out of parallelism with a horizontal plane and with the longitudinal axis of the coupler, whereby the opener is permitted to follow the tail of the knuckle and to exert its extreme leverage at any point during the 50 opening movement. This construction and arrangement of parts we believe to be new and to be of extreme importance.

It will be understood that the foregoing 55 description of the diagrammatic views and the action of the knuckle opener is not necessarily an absolutely exact geometric tangent to the movement of the knuckle tail but is substantially so at all points.

As illustrating the action of the opener we have shown in Figs. 7, 8 and 9, the relative positions of the opener in its normal inactive position, the position where the opening movement has just begun and the extreme opening movement respectively. It 60

will be seen that by means of this mounting, the opener is permitted bodily, vertical and horizontal movement, at the same time securing proper leverage without binding or friction. In the beginning of the opening 70 movement, the trunnion 42 is lifted from its seat and the opener moved bodily upward for a short distance. As the movement continues, the opener shifts sidewise, the trunnions finally bearing against the upper 75 extremities of the elongated bearing slots.

Upon reference to Fig. 2 it will be seen that there is shown in dotted lines the position of the lock and knuckle thrower when the knuckle is thrown to its extreme opening limit. It will also be seen that the locking block 31 is not nearly to its extreme limit of upward movement. This is a very important provision, inasmuch as the parts become worn through use and unless such 80 provision is made it will be found that the knuckle thrower will not have sufficient travel to completely open the knuckle. Therefore in our construction we have provided means whereby the knuckle may be 85 thrown to its extreme limit of opening even though the parts are considerably worn.

It will here be explained that while the lock block 31 has a limited movement longitudinally of the draw-head, in order that 90 it may be unseated from the lock set, it is held against movement transversely of the draw-head in a guideway formed by the knuckle kicker bearings 40 and 41 and the opposite upright wall of the recess in the 100 head of the coupler.

It will be noted that the construction of the link 36 and clevis 37 is such that when the parts are in their normal closed position, the opening in the top of the coupler head 105 is completely closed, thus excluding snow or dirt such as would tend to restrict the free operation of the coupler.

We are aware that this coupler may be modified in many ways from the precise 110 construction shown in the drawings and we do not therefore wish to be limited to the exact construction herein shown and described.

We claim:

1. A coupler, comprising, in combination, a coupler head, a knuckle pivoted therein, means for locking said knuckle in closed position, and a knuckle thrower mounted in said head and having a portion adapted to contact the tail of the knuckle, the said thrower being pivoted in loose bearings for compound movement whereby the direction of force applied by said thrower is at all times substantially tangent to the path of travel of said knuckle tail, substantially as described. 120

2. A coupler of the class described, comprising, in combination, a coupler head, a knuckle pivoted therein, means for locking 125

115

120

125

130

said knuckle in closed position, and a knuckle thrower pivoted within said coupler head out of parallelism with the longitudinal axis of said coupler and out of parallelism with a horizontal plane, the pivotal bearings for said thrower being arranged to permit a limited vertical movement thereof, substantially as described.

3. A coupler comprising, in combination, 10 a coupler head, a knuckle pivoted therein, means for locking said knuckle in closed position, and a thrower for opening said knuckle, trunnions on said knuckle thrower, bearings in said head for said trunnions, 15 said bearings being out of parallelism with a horizontal plane and with the longitudinal axis of said coupler and being so arranged as to permit a limited bodily, compound movement of said knuckle thrower, substantially as described.

4. A coupler comprising a coupler head, a swinging knuckle provided on its tail with a shoulder extending transversely thereof, a lock having a projection, and lock-setting 25 means including a lock set shoulder disposed to the rear of the front face of the lock, the projection on the lock frictionally and slidably engaging the forward face of the shoulder on the knuckle tail during opening 30 movement of the knuckle to positively draw the lock forwardly from its lock set position, and said projection being in frictional and slidable engagement with the front face of the shoulder on the knuckle tail during 35 closing movement of the knuckle to prevent the lock from going back on the lock set shoulder during the closing of the knuckle, substantially as described.

5. A coupler comprising a coupler head, a 40 swinging knuckle having a groove on the tail thereof eccentric to the pivot of the knuckle, a locking member, and lock-setting means including a lock set shoulder disposed to the rear of the front face of the lock, said 45 locking member being provided on the forward lower portion thereof with a projection depending below the bottom of the locking member and lying in the groove during the opening movement of the knuckle to 50 positively draw the lock forwardly from its lock set position, and said projection lying in the groove during the closing movement of the knuckle to prevent the lock from going back on the lock set shoulder during the 55 closing of the knuckle, substantially as described.

6. A coupler comprising a coupler head, a swinging knuckle, a lock, a lock-set in rear of the front face of the lock, and a positive

sliding interengagement between the lock 60 and the knuckle during the opening movement of the knuckle to draw the lock forwardly from the lock set, the lock and the knuckle also being in positive slidable interengagement during the closing movement of 65 the knuckle to prevent the lock from going back on the lock set during the closing of the knuckle, substantially as described.

7. A coupler comprising a coupler head, a swinging knuckle having a tail provided in 70 the upper face with a groove eccentric to the pivot of the knuckle and extending entirely across the tail, a lock, and a lock set in rear of the front face of the lock, said lock being provided upon its bottom with a projection 75 lying in the path of the rear wall of the groove during the opening movement of the knuckle and while the lock is on the lock set, to draw the lock forwardly from the lock set during the opening movement of the 80 knuckle, the projection being outside of the respective ends of the groove in the extreme open and closed positions of the knuckle, and the knuckle tail being provided with a lateral extension forming a continuation of 85 the rear wall of the groove, the projection on the lock lying in front of the extension in the extreme open position of the knuckle to prevent the lock from going back on the lock set, substantially as described. 90

8. A coupler comprising a coupler head, a swinging knuckle having a transverse shoulder on the tail thereof, a lock, and a lock-set shoulder on the head in rear of the front face of the lock, said lock having a 95 seat portion to seat upon the lock-set shoulder and also provided at its front with a depending portion to engage the front wall of the shoulder on the knuckle tail and thereby hold the lock with its seat portion below the 100 lock-set shoulder when the lock is dropped from an elevation above the lock set position and in an open position of the knuckle, substantially as described.

9. A coupler comprising a coupler head, a 105 swinging knuckle, a vertically-movable lock, a knuckle kicker, and bearings for the knuckle kicker, the lock lying between the bearings and one wall of the coupler head, said wall and bearings forming a vertical 110 guideway for the lock and preventing side-wise movement thereof transversely of the head, substantially as described.
